OVERLAPPING AND INTERLOCKING LOUVERS
FOR LIGHT FIXTURES

William D. Cahill, Chicago, Ill., assignor, by mesne assignments, to Curtiss-Electro Lighting, Inc., a corporation of Illinois

Filed Sept. 13, 1957, Ser. No. 683,820
5 Claims. (Cl. 240—9)

My invention relates to light diffusing plastic louvers for light fixtures and luminous ceilings, which may be associated together in any length without visible attaching means and which overlap and interlock.

Another object of my invention is to provide overlapping and interlocking louvers, which need no cross bars, or other extraneous and visible attachments.

To supply louvers for forming a light fixture or luminous ceiling of any size by the mere attachment of louvers of standard size. Unlike any other suspended ceiling, the architect can utilize my overlap and interlock louvers in a simple aesthetic linear designed ceiling without visible grid crossbars across the width. Through their use not only are crossbars eliminated but the standard architectural module of 2 foot widths is used so that the length can be 2 feet or 2,000 feet.

To create louvers having overlapping and reverse interlocking features. This prevents sidewise misalignment.

The overlapping and interlocking construction of my louvers will straighten out slight warping and retain the louvers in straight aligned position.

In attaching of my louvers together, they have the appearance of a single piece, with greater resultant saleability and marketability.

My invention also contemplates ease of installation and attachment of my louvers by any one without special skill and such other objects, advantages and capabilities as will later more fully appear, and which are inherently possessed by my invention.

While I have shown in the accompanying drawings a preferred embodiment of my invention, yet it is to be understood that the same is susceptible of modification and change without departing from the spirit of my invention.

Referring to the drawings, FIG. 1 is a plan view of two of my louvers in assembled position; FIG. 2 is a broken edge view; FIG. 3 is a prospective view of two of my louvers about to be joined; FIG. 4 is a plan view of my coupled louvers, and FIG. 5 is a detailed sectional view of the louvers partly separated and showing the alignment on line 5—5 of FIG. 1.

The embodiment selected to illustrate my invention includes two or more louvers adapted to overlap and interlock without visible attachments to form the light diffusing portions of a lighting fixture or luminous ceiling.

My louvers 10 are formed of plastic, glass or other suitable material for diffusing fluorescent electric light or the like positioned adjacent them. My louvers have a body portion 11 preferably formed of spaced crossed strips forming a plurality of squares or cube portions with open ends. Each louver has spaced long sides 12 and 13 and spaced ends 14 and 15.

A marginal band 16 extends around one end 14 of the louver and terminates at 17 short of the center of each of said long sides 12 and 13. Another marginal band 18 extends around the other end 15 and terminates at 19 short of the center of each of said long sides 12 and 13. The distance between 17 and 14 is the same as the distance between 19 and 15.

In one form of my louver 20, marginal band 16 covers the upper half of the ends of strips 21 and the spaces therebetween. A central marginal band 22 extends be-

2

tween 17 and 19 on each of long sides 12 and 13 and covers the lower half of the ends of strips 21 and the spaces therebetween.

At 17 and 19, strips 21 and bands 16 and 18 have inwardly cut corner notches 23 and 24. The outer ends of each central marginal band 22 and connecting strip 21 have inwardly cut corner notches 25 and 26.

A adjacent louver referred to as 27 may be formed as heretofore set forth with the following differences: This adjacent louver 27 has its marginal bands 16 and 18 covering the lower half of the ends of strips 21 and the spaces therebetween, and its central marginal band 22 covering the upper half of the ends of strips 21 and the spaces between 17 and 19.

When louver 27 is to be attached to louver 20 central marginal band 22 of louver 27 is positioned on top of central marginal band 22 of louver 20, with corner notches 25 and 26 of louver 27 engaging corner notches 23 and 24 of louver 20. This positions marginal band 16 and 18 of louver 20 against and on top of marginal band 16 and 18 of louver 27.

Further louvers 20 and 27 may be similarly attached to each other until a fixture or luminous ceiling of desired size is obtained. Means are then provided for attaching the fixture or luminous ceiling so formed to the ceiling of a room and fluorescent electric or other light are provided for supplying illumination to be distributed or diffused by the fixture or luminous ceiling.

It is also to be noted that by turning over louver 20, louver 27 is obtained so that louvers 10 are reversible.

Having thus described my invention, I claim:

1. A louver for light fixtures comprising a rectangular body member having a plurality of crossing strips forming a plurality of longitudinally and laterally spaced cubes with open marginal ends, said body member having spaced sides and spaced ends, a marginal band beginning short of center on one of said sides and extending around one end to a point short of center on the other side, another marginal band beginning short of the other side of center on said side and extending around the other end to a point short of center on the other side, said marginal bands covering the upper half of the marginal ends of said strips, a central band covering the lower half of the marginal ends of said strips and extending between said marginal bands, said marginal bands at their ends and the marginal open ends of said strips at their meeting having cooperating notches and said central bands at their ends also having cooperating notches at their meeting with the marginal open ends of said strips.

2. A louver for light fixtures comprising a rectangular body member having a plurality of crossing strips forming a plurality of longitudinally and laterally spaced cubes with open marginal ends, said body member having spaced sides and spaced ends, a marginal band beginning short of center on one of said sides and extending around one end to a point short of center on the other side, another marginal band beginning short of the other side of center on said side and extending around the other end to a point short of center on the other side, said marginal bands covering the lower half of the marginal ends of said strips, a central band covering the upper half of the marginal ends of said strips and extending between said marginal bands, said marginal bands at their ends and the marginal open ends of said strips at their meeting having cooperating notches and said central bands at their ends also having cooperating notches at their meeting with the marginal open ends of said strips.

3. A pair of interlocking and overlapping louvers for light fixtures comprising two louvers, each having a body member having a plurality of crossing strips forming a plurality of longitudinally and laterally spaced cubes with

open marginal ends, said body member having spaced sides and spaced ends, a marginal band beginning short of center on one of said sides and extending around one end to a point short of center on the other side, another marginal band beginning short of the other side of center on said side and extending around the other end to a point short of center on the other side, a central band extending between said marginal bands, said marginal bands at their ends and the marginal open ends of said strips at their meeting having cooperating notches and said central bands at their ends also having cooperating notches at their meeting with the marginal open ends of said strips, the marginal bands in the first of said louvers covering the upper half, and the marginal bands in the second of said louvers covering the lower half of the marginal ends of said strips, and the central band of the first louver covering the lower half and the central band of the second louver covering the upper half of the marginal ends of said strips between the marginal bands, so that the marginal band of the first louver rests on the marginal band of the second louver, and the central band of the second louver rests on the central band of the first louver as the louvers interengage and lock at said notches.

4. A louver for light fixtures comprising a rectangular body member having a plurality of crossing strips forming a plurality of longitudinally and laterally spaced cubes, said body having spaced sides and spaced ends, a bar portion beginning short of center on one of said sides and extending to one of said spaced ends, another bar portion beginning short of center of said one side and extending to the other of said spaced ends, said bar portions covering the upper half of said one side, a central bar covering the lower half of said one side and extending between said bar portions, said bar portions at their ends and the open ends of said strips at their meeting forming

cooperating notches and said central bar at its ends also forming cooperating notches at its meeting with the open ends of said strips.

5. A pair of interlocking and overlapping louvers for light fixture comprising two louvers, each louver having a body member having a plurality of crossing strips forming a plurality of longitudinally and laterally spaced cubes, said body member having spaced sides and spaced ends, a bar portion beginning short of center on one of said sides and extending to one of said spaced ends, another bar portion beginning short of center on said side and extending to the other of said spaced ends, a central bar extending between said bar portions, said bar portions at their ends and the open ends of said strips at their meeting forming cooperating notches and said central bar at its ends also forming cooperating notches at its meeting with the open ends of said strips, the bar portions in the first of said louvers covering the upper half of said side, and the bar portions in the second of said louvers covering the lower half of said side, and the central bar of the first louver covering the lower half of said side and the central bar of the second louver covering the upper half of the said side, so that the bar portions of the first louver rests on the bar portions of the second louver, and the central bar of the second louver rests on the central bar of the first louver as the louvers interengage and interlock at said notches.
